CONTAINER AND METHOD OF FORMING
SAMEChester M. MacChesney, Chicago, Ill., assignor to
Acme Steel Company, Chicago, Ill., a corpora-
tion of Illinois

Application May 18, 1931, Serial No. 538,094

15 Claims. (Cl. 217—89)

This invention relates to improvements in containers and methods of forming the same and its purpose is to provide a container, adapted for use as a butter tub or the like, having a cover comprising an annular rim which is adapted to form a detachable interlocking engagement with a hoop passing around the container. It has been the usual practice in the prior art to secure covers on butter tubs by means of metal clips which are nailed to the cover and to the side of the tub but this method of fastening is objectionable because of its inconvenience, the likelihood of contamination of the butter by nails passing through the wall of the tub, and the difficulty of again securing the cover in place after it has once been removed. Efforts have heretofore been made to secure covers upon tubs without the use of nails but the tubs which have been provided for this purpose have not been such as to permit the replacement of the cover after it has once been removed or they have not been of such construction that any one of a group of covers might be applied to any one of a large number of tubs, because of variations in manufacture.

The principal object of the present invention is to provide an improved container having a cover provided with an annular metal rim which interlocks with a metal hoop passing around the upper part of the tub. Another object is to provide an improved method of forming a container according to which a metal band is formed to provide an annular projection which engages an annular groove in the tub, and with an annular shoulder which is detachably engaged by inwardly projecting parts carried by a metallic rim attached to the cover. A further object of the invention is to provide a container having a cover adapted to seat upon a tub with an annular metallic rim attached to the cover and provided with inwardly projecting parts of peculiar formation adapted to facilitate the removal of the cover from interlocking engagement with a hoop secured to the tub. Another object is to provide an improved form of reinforcing hoop for a tub. Other objects relate to various features of construction and arrangement, and to details of the method, which will appear more fully hereinafter.

The nature of the invention will be understood from the following specification taken with the accompanying drawings, in which the improved method is illustrated in connection with one form of the improved container. In the drawings,

Fig. 1 shows a perspective view of a butter tub

or other container embodying the features of the present invention;

Fig. 2 is an enlarged side elevation of the upper portion of the container illustrated in Fig. 1, illustrating the cover and rim in the process of being removed from the tub;

Fig. 3 is a perspective view of a portion of the uppermost hoop which is secured around the tub;

Fig. 4 is a perspective view of a portion of the metal band from which the rim of the cover is formed;

Fig. 5 is a perspective view of a portion of the rim in an intermediate stage of its manufacture;

Fig. 6 is a perspective view of a portion of the completed rim;

Fig. 7 is a vertical section taken on the line 7—7 of Fig. 6;

Fig. 8 is a vertical section taken on the line 8—8 of Fig. 6;

Fig. 9 is a horizontal section taken on the line 9—9 of Fig. 6;

Fig. 10 is a vertical section through the upper edge portion of the container, showing the interlocking of the rim with the uppermost hoop and showing the manner of inserting a screw driver or other tool to pry the rim out of interlocking engagement with the hoop; and

Fig. 11 is a sectional view similar to that of Fig. 10, showing the rim after it has been pried out of interlocking engagement with the hoop.

The invention is illustrated as being embodied in a container comprising a tub or vessel 15 having an annular upwardly flared wall formed by a plurality of wooden staves 16. The lower ends of these staves engage the outer edge of the circular bottom wall of the tub and are secured in this relationship by a surrounding hoop 17 which may have a bead 17^a around its upper edge and an inwardly extending flange around its lower edge to underlie the lower ends of the staves. At points between the upper and lower ends of the staves, they are surrounded by a pair of similar metal hoops 18 which are preferably provided with beads 18^a around their lower edges and which are driven onto the upwardly flared wall of the tub from the lower wall thereof until they have a tight engagement therewith. During the driving of these hoops onto the tub, the metal thereof is adapted to stretch around the upper edge of the hoop to permit it to conform to the flare of the tub. These features of construction do not in themselves constitute a part of the present invention.

The invention resides more particularly in the method by which the circular wooden cover 19 is secured in position on the tub and for this purpose the tub is provided around its upper edge 5 with an annular metal hoop 20 which has the form illustrated particularly in Figs. 3, 10 and 11. This hoop 20 is formed by taking an elongated strip of sheet metal, having considerable stiffness and some ductility, and operating upon it by 10 suitable dies and the like to impart to it the irregular formation shown in the drawings, where it is illustrated as having a centrally located inwardly extending projection 20^a, of U-shaped cross-section, thus forming an annular groove 15 20^b on the outer side of the hoop, bounded on its upper side by the annular outwardly extending projection 20^c and on its lower side by the annular outwardly extending projection 20^d. From the projections 20^c and 20^d the metal of the hoop 20 flares upwardly and downwardly, respectively, to 25 form the edges 20^e which are adapted to lie in close contact with the wall of the tub when the hoop is in position thereon. The annular wall of the tub, formed by the staves 16, is provided 30 a short distance below the upper edge thereof with an annular groove 21 and after the metal band having the irregular contour, shown in Fig. 3, has been formed, the ends thereof are secured together by riveting, spot welding and the like, to form the annular hoop 20 which is driven 35 upwardly over the flaring wall of the tub from the bottom thereof until the inwardly extending projection 20^a snaps into engagement with the annular groove 21. The hoop 20 may preferably be applied by pressing the staves of the tub inwardly to reduce the cross-section of the tub temporarily while the hoop 20 is being applied so that when this pressure is released, the staves will expand to their normal positions and thus cause the 40 annular projection 20^a to assume an interlocking engagement with the groove 21. When in this position, the upper edge 20^e of the hoop 20 lies substantially flush with the upper edges of the staves and the lower edge 20^e lies in close contact with the annular wall of the tub, as shown in 45 Fig. 10. The annular projection 20^c of the hoop preferably extends outwardly to a lesser extent than the lowermost projection 20^d.

The cover 19, formed preferably of wood, is 50 adapted to seat upon the upper ends of the staves 16, as shown in Fig. 10, and it may overlap the upper edge of the hoop 20. The cover is provided around its outer edge with an annular groove 19^a bounded on its upper side by an annular shoulder 55 19^b having a diameter somewhat less than that of the lower part 19^c of the cover which directly engages the tub. The cover is provided below the groove 19^a with a downwardly and outwardly flaring annular surface 19^d. These parts are provided for the purpose of forming an interlocking engagement with the annular metal rim 22 which is also adapted to interlock with the metal hoop 20. This rim 22 is formed from an elongated flat strip of sheet metal 23, illustrated in Fig. 4. This 60 strip of metal is provided along its upper edge with an inwardly extending inclined flange 22^a provided with a series of transverse corrugations 22^b which may be formed in the upper edge of the band before this part is bent to form the inclined flange. After the flange 22^a and the bead 22^c have been formed on the band 23, as illustrated 65 in Fig. 5, the portion of the band which lies below the inclined flange 22^a is operated upon to form a series of transverse grooves 22^d which are formed 70 by compressing the body of the metal band, as

well as the bead 22^c, at intervals, to form the outwardly extending body projections or corrugations 22^d which have a gradual outward flare from the upper part of the band to the lower edge thereof. As a result of the compression of the bead 22^c at intervals, there are formed a series of inwardly extending projections or teeth 22^e formed by those parts of the bead 22^c which have not been compressed and which lie between the corrugations 22^d. The band then has the completed form shown in Fig. 6 and a suitable length thereof is bent into annular form and the ends thereof secured together by rivets, spot welding or the like to form the completed annular rim 22 which is applied to the cover 19 by pressing it downwardly over the cover with sufficient pressure to cause the annular inclined flange 22^a to snap over the annular shoulder 19^b of the cover into interlocking engagement with the annular groove 19^a of the cover, as shown in Fig. 10. The transverse corrugation of the flange 22^a permits sufficient expansion of the annular flange 22^a to permit this flange to be snapped over the shoulder 19^b on the cover and, when the rim is in place, the flange 22^a lies in contact with the annular inclined surface 19^d of the cover. The body portion of the rim 22 then depends below the lower edge of the cover 19 with the projections 22^e extending inwardly from its lower edge.

The circular cover 19, with the rim 22 attached thereto, is applied to the tub 15 by passing the lower part of the rim downwardly over the upper portion of the hoop 20 until the rounded surfaces of the projections 22^e on the rim engage the upper inclined annular surface of the projection 20^c on the hoop. Then, upon applying further pressure, the rim 22 expands sufficiently to permit the projections 22^e to snap over the annular projection 22^c on the hoop with the result that these projections then engage the annular groove 20^b in the hoop 20 with the upper edges of the projections 22^e contacting with the under side of the projection 22^c, as shown in Fig. 10. The cover is then secured firmly on the tub and retains that position unless intentionally removed therefrom. Due to the fact 105 that the position of the hoop 20 on the tub is determined by the engagement of the projection 20^a of the hoop with the annular groove 21 in the tub, the hoop 20 has a definite location on every tub, at a predetermined distance below the upper 110 edge thereof, and the rim 22 is so formed that the inwardly extending projections 22^e thereof are located at predetermined distances below the lower surface of the cover 19. This predetermined 115 relationship is effected by properly locating the grooves 21 and 19^a in the tub and the cover, respectively, and, even though there be some slight variation as between different tubs and covers of a series, the teeth or projections 22^e of any rim 120 will nevertheless form an interlocking engagement with the groove 22^b of the hoop applied to any tub so that there is no necessity of selecting any particular cover for application to any particular tub.

Since the annular groove 20^b in the hoop has a somewhat greater vertical dimension than the vertical dimension of those parts of the annular bead on the rim which form the projections 22^e, some variation from the preferred predetermined 140 relative locations of the shoulder 20^c and projections 22^e is permitted without interfering with the interlocking engagement of the projections with the annular groove 20^b and, at the same time, sufficient space is provided in the groove 20^b, below 145 150

the lower edge of the rim 22, to permit the insertion of a screw driver or other tool 24, as shown in Fig. 10, for the purpose of detaching the rim from the tub. When it is desired to remove the cover, 5 the tool 24 is inserted into the groove 20^b beneath the lower edge of the rim and then, upon pressing downwardly upon the handle of the tool, as shown in Fig. 2, the lower edge of the rim may be pried upwardly over the projection 20^c of the hoop 20. 10 When this has been effected at one point around the circumference of the tub, the teeth or projections 22^e of the hoop engage the annular projection 20^c in such a way as to prevent a return movement of that portion of the rim when the tool is 15 withdrawn. The tool is then inserted successively at adjacent points around the circumference of the rim until a sufficient portion thereof has been pried upwardly over the projection 20^c to permit the removal of the cover. During this operation, 20 the tool or screw driver 24 coacts with the projection 20^d which constitutes the lower wall of the groove 20^b and to facilitate this action, this projection is preferably extended outwardly to a point flush with or slightly beyond the outer peripheral surface of the rim 22. It will be apparent that the interlocking engagement described above could be effected by having a continuous annular bead 22^c on the lower edge of the rim to pass into interlocking engagement with the groove 25 20^b of the hoop but a continuous annular bead is not well adapted for permitting the ready removal of the cover because, after the tool 24 has been inserted at one point to pry one edge portion of the rim upwardly over the shoulder 20^c, that portion of the bead tends to return to engagement with the groove when the tool is withdrawn and the use of two or more tools would often be required to effect the removal of the cover. However, by providing the teeth or projections 22^e, the 30 lower edge of the rim is adapted to grip or interlock with the projection 20^c when one portion thereof is pried upwardly, so that the tool 24 may be withdrawn and used at other points for prying upwardly other parts of the rim. The method of 35 forming the projections 22^e by compressing portions of the rim together with portions of the previously formed bead 22^c, causes the lower edge of the rim to have sufficient strength and stiffness to prevent permanent stretching thereof when it 40 is removed from the tub and thus the same cover and rim may be removed and reapplied several times to or from the same or different tubs. In addition to providing means for facilitating the removal of the rim from the hoop by the use of 45 a single tool applied at successive points around the hoop, the formation of the enlarged transverse corrugations of the body portion of the rim 22 also renders the rim somewhat yieldable circumferentially, which facilitates the action of 50 snapping the rim over the annular shoulder 20^c on the hoop. The extension of the lower projection 20^d outwardly beyond the outer portion of the rim prevents the accidental removal of 55 the cover by engagement of the rim with any adjacent object. It will be seen that the hoop 20 carried by the vessel 16 has an annular groove 20^b therein while the cover 19 has an annular groove 19^a therein so that the construction provides two 60 annular grooves, one carried by the vessel and the other by the cover, in combination with an annular metallic rim 22 having one annular corrugated part 22^a adapted to be snapped into engagement with one of these grooves and another 65 70 annular part comprising the sectional bead which

is adapted to be snapped into engagement with the other groove.

Although one form of the improved container and one method of forming it have been shown and described by way of illustration, it will be 80 understood that the invention may take various forms and may be practiced in various ways within the scope of the appended claims.

I claim:

1. The combination in a container, of a non-metallic vessel, an annular sheet metal hoop surrounding the upper part of said vessel and having an annular recess therein, a non-metallic cover for said vessel, and an annular sheet metal rim attached to said cover and having inwardly extending parts adapted to snap into engagement with said annular recess, said recess having an annular space beneath the lower edge of said rim to permit the insertion of a tool for prying said rim out of engagement with said hoop. 85 90 95

2. The combination in a container, of a vessel having an annular groove therein adjacent its upper end, a sheet metal hoop having an annular part engaging said groove and an annular shoulder projecting outwardly therefrom, a cover for 100 said vessel, and an annular rim attached to said cover and having parts adapted to snap over said shoulder when said cover is forced downwardly onto said vessel.

3. The combination in a container, of a vessel, 105 a hoop surrounding the upper part of said vessel, a cover for said vessel, and a rim attached to said cover and having a transversely corrugated depending portion provided with inwardly extending spaced projections detachably interlocking 110 with said hoop.

4. The combination in a container, of a vessel, a hoop surrounding the upper part of said vessel, a cover for said vessel, and a sheet metal rim attached to said cover and having inturned spaced 115 bead-sections along the lower edge thereof detachably interlocking with said hoop.

5. The combination in a container, of a vessel, an annular sheet metal hoop surrounding the upper part of said vessel and having spaced annular shoulders extending outwardly therefrom, 120 a cover for said vessel, said vessel having an annular groove engaged by a part of said hoop between said shoulders and an annular rim attached to said cover and having parts adapted to 125 extend inwardly beneath the upper one of said annular shoulders.

6. The combination in a container, of a vessel, an annular sheet metal hoop surrounding the upper part of said vessel and having a pair of 130 spaced annular shoulders projecting outwardly therefrom, the lower one of said shoulders projecting farther than the upper one, a cover for said vessel, and an annular sheet metal rim attached to said cover and having inwardly extending parts at its lower edge to interlock with the under side of the upper one of said annular shoulders. 135

7. The combination in a container, of a wooden vessel having an upwardly flared annular wall 140 provided with an annular groove adjacent its upper end, a sheet metal hoop surrounding said vessel and having an inwardly extending part engaging said groove, said hoop being provided on its outer side with an annular shoulder, a 145 cover for said vessel, and an annular rim attached to said cover and having inwardly extending spaced teeth to interlock detachably with the underside of said annular shoulder.

8. The combination in a container, of a vessel, 150

- 5 a cover for said vessel, said cover and said vessel being provided with annular parts having annular grooves therein, and a sheet metal rim having annular parts snapped into engagement with one of said grooves and other parts snapped into engagement with the other of said grooves for holding said cover on said vessel. 80
- 10 9. The combination in a container, of a cover, and a sheet metal rim attached to said cover and having a depending portion provided with spaced transverse corrugations and with an inwardly extending projection between each pair of adjacent corrugations. 85
- 15 10. The method of forming a container which consists in providing a vessel having an annular groove therein, forcing onto said vessel a hoop having a part adapted to snap into engagement with said groove and having an annular shoulder, and forcing downwardly onto said vessel a cover provided with a depending transversely corrugated rim having spaced inwardly extending bead-sections to interlock with said shoulder. 90
- 20 11. The method of forming a container rim which consists in providing a metal band with an annular bead along one edge thereof and then compressing said bead and said band at intervals to form transverse corrugations, the intervening portions of said band forming projections. 95
- 25 12. The combination in a container, of a wooden vessel having an upwardly flaring annular wall provided with an annular groove adjacent its upper end, a metallic hoop surrounding said vessel and having annular corrugations forming an annular recess on the outer side thereof and an annular projection on the inner side thereof said annular projection being snapped into engagement with said groove when said hoop is applied to said vessel, a non-metallic cover for said vessel, and an annular metallic rim secured on said cover and having a depending annular portion projecting over said hoop and terminating at its lower edge in inwardly extending parts adapted to be snapped over one of said annular corrugations into said recess by the momentary expansion of said rim. 100
- 30 13. The combination in a container, of a wooden vessel, a metallic hoop surrounding the upper part of said vessel and having an annular recess, a wooden cover for said vessel having an annular groove in its outer edge, and an annular metallic rim having an inwardly extending part around its upper edge snapped into engagement with said groove, and an inwardly extending part around its lower edge snapped into engagement with said recess in said hoop. 105
- 35 14. A container comprising a vessel having an annular recess therein adjacent its upper edge, an annular hoop having an inwardly extending bead engaging said recess and having an outwardly extending annular bead, a cover for said vessel, and a rim having a part overlying said cover and having another part extending inwardly beneath said last named bead. 110
- 40 15. A container comprising a vessel having an annular recess therein adjacent its upper edge, an annular sheet metal hoop surrounding said vessel and having an inwardly extending annular bead formed therein to engage said recess, said hoop having also an outwardly extending annular bead, one wall of which is a continuation of the upper portion of said first-named bead, thereby forming an annular shoulder, a cover seated on the upper edge of said vessel, and an annular metallic rim having a part overlying said cover and having an inwardly extending annular flange along its lower edge coacting with said shoulder. 115
